UNITED STATES PATENT OFFICE

1,968,086

FIRE EXTINGUISHING APPARATUS

Daniel Mapes, Mamaroneck, N. Y., assignor to
 Walter Kidde & Company, Inc., New York, N. Y.,
 a corporation of New York

Application August 31, 1927, Serial No. 216,508
 Renewed October 24, 1929

14 Claims. (Cl. 169—11)

The present invention relates to fire extinguishing apparatus of the type wherein the extinguishing medium is stored in suitable containers under the pressure of its own vapor. The 5 fire extinguishing agent commonly used in these systems is carbonic acid gas which is maintained in liquid form in the containers under the extreme pressure of its vapor and a system of pipes is coordinated with the containers to enable the 10 fluid to be discharged at desired locations where the protection is to be afforded.

A system of the above character is illustrated in the United States Patent No. 1,335,394 dated March 30, 1920, and the number of containers 15 supplying such systems may be varied to suit the demands of a particular installation. Contrary to the practice and belief now current, it has been found that pipes of relatively large diameters may be used in these systems, the construction 20 being qualified by the use of connections which insure the speedy discharge of the fluid from all of the containers simultaneously.

Where an installation requires the number of containers to be multiplied greatly, the difficulty 25 of providing a means for effecting discharge from the entire bank or gang of containers simultaneously and effectively is confronted. It has been found that there is a practical limit to the number of containers which can be controlled by 30 direct manual force and the present invention relates to systems wherein the number of containers renders the manual control thereof difficult, if not impossible.

Accordingly, by the present invention, it is 35 proposed to employ the expansive force of the extinguishing medium itself to effect the release of the extinguishing medium from all of the containers as desired and in the embodiment described herein, certain containers, described as 40 master control containers, are set aside to supply the medium to actuate the releasing mechanism of the main supply containers.

As a further object of the invention, it is proposed to provide an automatic safety mechanism 45 which will prevent the actuation of the main containers if the pressure in the master control containers becomes excessive by reason of temperature rise while the discharge of the extinguishing medium is not needed.

50 Other objects of the invention will appear as the description proceeds and reference will now be had for a more detailed description of the invention to the accompanying drawings forming a part hereof wherein:

55 Figure 1 is a view in elevation showing an in-

stallation comprising a plurality of containers provided with a suitable number of operating devices according to the present invention.

Figure 2 is a view in elevation showing master control cylinders arranged to provide a supply 60 of gas under pressure for operating the gang releases shown in Figure 1.

Figure 3 is a view in elevation, partly in section, showing the devices for releasing the gas 65 from the master control cylinder, with one form of a safety device to be described.

Figure 4 is a view in elevation of the spacing washer used in connection with the release device of Figure 3.

Figure 5 is a view in section taken on line 5—5 70 of Figure 4 and looking in the direction of the arrows.

Figure 6 is a sectional view of the pressure gang release mechanism shown generally in Figure 7.

Figure 7 is a view in elevation showing an installation arranged to operate in accordance with the general principles of this invention, but showing means whereby the medium, which is supplied from the master control cylinders to operate the pressure gang release, is returned to the main fire extinguishing medium discharge line after such operation.

Figure 8 is a view in sectional elevation of a preferred form of safety device for the master 85 control cylinder.

Figure 9 is a plan view of the parts shown in Figure 8 with the cap removed.

Referring particularly to Figure 1, reference character *a* designates containers of a suitable 90 fire extinguishing medium, such as carbonic acid gas in liquid form, which is maintained under the extreme pressure of its own vapor. These banks or gangs of containers are provided with releasing devices *b*, which may be of the frangible disc type wherein the discs are ruptured by tubular cutters *i* carried by threaded shafts *i'* arranged to be operated together to effect the simultaneous discharge of the medium from all of the containers, the cutter and shaft being 100 shown in detail in Figure 3. Conduits *b'*, conduct the medium from the respective containers to discharge lines *b''*, which conduct it to the points at which it is to be used to extinguish fires. Arms *b''*, secured to the shafts *i'* are connected to be 105 moved simultaneously by means of links *b''* which are rigidly connected together. A suitable structure *a'* may be provided to support the containers in their operative positions.

In order that all of the containers of each gang 110

may be operated simultaneously, the links b^4 are actuated, in their rupturing movement, by cables c passing over suitable pulleys c' , and connected to rods c^2 , as shown at c^3 . A covering c^4 protects the cable from accidental movement and thus insures operation only by the releasing devices through the actuating mechanism to be described later. Mounted beneath the cables c , are piston guides d , a medium under pressure being supplied thereto through conduit e . In this conduit, a bleeder nozzle e' is provided to prevent a gradual accumulation of pressure in the conduit e from actuating the releasing mechanism when a slow leak exists in the control cylinders.

15 Conduit e^2 is connected to the conduit e and carries the actuating medium from the master control cylinders f in Figure 2. Cylinders f are provided with disc rupturing devices in accordance with designs proposed by the present invention which, in this figure, are represented generally by the reference character f' . Conduits f^2 carry the medium from the disc rupturing devices to the conduit e^2 and the rupturing devices are actuated through levers f^3 which are connected 20 for simultaneous movement by link f^4 . To insure the positive actuation of the rupturing devices, weights f^5 are connected to the respective levers f^3 and are prevented from moving by link f^6 which is engaged over a shoulder g' of a trigger operated by release lever g . The entire master control mechanism is mounted upon a suitable weight indicating mechanism h so that loss 25 in weight may be detected due to the escape of the medium from the cylinders.

30 35 The improved form of disc rupturing device, mentioned in connection with the construction indicated by the reference character f^1 is shown in detail in Figure 3 wherein f^3 represents the operating lever, mentioned above. A tubular cutter i , to which lever f^3 is secured, is provided with a threaded portion i' to cause the cutter i to be advanced axially during movement of lever f^3 . The fittings which secure the cutter to the valve j form no part of this invention and are designated generally by the reference character i^2 . This same cutter mechanism is used in connection with the disc rupturing devices b of Figure 1. Threaded block i^3 carried with the valve j is adapted to seat gaskets j' between which are carried two frangible discs j^2 and j^3 . These discs are spaced by an annular washer j^4 which, in Figures 4 and 5, is shown to be provided with radial grooves j^5 . The frangible disc j^2 , which is in direct contact with the medium within the cylinder, is designed to rupture at a lower pressure than the disc j^3 . This prevents the operation of the entire apparatus due to the bursting of the frangible disc of a control cylinder, should excessive pressure be produced therein. From the 40 rupture of the first disc j^2 , the medium escapes through the radial slots j^6 and port j^6 , into the atmosphere, thus relieving the pressure from disc j^3 and preventing the rupture thereof.

45 50 55 The pressure gang releasing mechanism, indicated generally at d in Figure 7, is shown in detail in Figure 6, wherein c^2 designates the piston rod connected to the piston. The piston guide is indicated at d and a suitable guide bonnet at d' . The piston rod is carried in the bonnet through 60 a suitable packing d^2 and packing nut d^3 . Inlet port d^4 in the guide bonnet serves to introduce the medium in back of the piston to force it through the piston guide. Reference character k indicates a piston which is carried slidably 65 within the piston guide d and is provided with

a pliable cover k' to insure a gas-tight connection. A passage k^2 extends through the piston and provides a communication from one side thereof to the other. The pin k^3 extends across the passage k^2 and forms a seat for a coiled spring k^4 which normally maintains a check k^5 away from its seat within the piston, thus permitting the passage of a slowly accumulating medium to the exhaust side of the piston guide. Strap k^6 prevents the check k^5 from becoming 80 dislodged and serves as an outer limit to its movement. A discharge port d^6 , at the lower end of the piston guide, permits the discharge of the actuating medium from the piston guide, after the piston has moved to its extreme lower position, during which movement the disc rupturing devices on the containers have been actuated. In the end of the lower bonnet d^6 , passages d^7 are provided to permit the escape of fluid which may be confined within the bonnet 85 after the piston has passed the discharge port. A relief valve d^8 , is seated by a spring d^9 which, in turn, is seated by the bolt, nut and washer d^{10} . The entire mechanism may be supported upon a flange d^{11} , which is secured to a support 90 by an intervening spacer ring d^{12} . In the normal operation of the device, the piston is at the end of the piston guide nearest the upper bonnet d^1 . A sleeve k^7 prevents the piston from riding past the inlet d^4 . Upon the admission of 95 a medium under pressure through the inlet, the check k^5 in the piston k closes the passage k^2 and the piston is moved away from the upper bonnet d^1 . When the outlet d^6 is reached the actuating medium escapes therethrough. It will 100 be apparent that the check k^5 prevents the operation of the piston due to the low pressure produced by a gradual leakage of the medium into the piston guide but when the medium is introduced under full pressure the check is unable 105 to remain open, and the piston is actuated. The relief valve d^8 prevents moist air from entering the piston guide and corroding the interior surface thereof.

110 Figure 7 shows a slightly modified system 120 wherein the containers a are arranged similarly to those in Figure 1. The disc rupturing devices b , b^3 and b^4 are similar to those described in connection with Figure 1, and the conduits b' and b^2 may also be similar to the corresponding 125 elements of Figure 1. At the right of this figure, control cylinders f are provided and may have disc rupturing devices f' similar to those previously described in connection with Figures 2, 3, 4 and 5. The several disc rupturing devices 130 are connected together for simultaneous operation by the link f^4 and the medium discharged from the containers f is carried through conduit e^2 to the pressure gang release mechanism indicated at d . In the conduit e^2 is provided a valve e^3 , operated by a weighted arm e^4 . A pull cord e^5 serves to open a valve e^3 to permit the flow of the medium through the conduit e^2 when the disc rupturing devices f' have been actuated through the flexible connection e^6 between the 135 link f^4 and lever e^4 . The flexible link permits the valve e^3 to be seated tightly regardless of the position of the link f^4 , and thus the medium is prevented from passing through the conduit e^2 unless the cord e^5 has opened the valve. At the 140 bottom of the pressure gang release, a conduit e^7 is connected to the discharge outlet d^6 of the releasing mechanism and carries the discharged medium to the main discharge line b^2 . A check valve e^8 is provided in the conduit e^7 to prevent 145 150

the building up of a back pressure on the piston of the pressure gang release *d* to prevent the operation thereof. It will be apparent, from the above description, that the medium which has been utilized to release the main containers, is returned to the main discharge line and utilized as a fire extinguishing medium.

Figures 8 and 9 illustrate a preferred form of disc rupturing device for use with the master control cylinders. Instead of providing spaced frangible discs *j*² and *j*³ as described in connection with Figures 3, 4 and 5, the fitting *j*' is provided with a valve stem *l* having an axial drilling *l*' through which the medium within the container might pass under certain conditions. The threaded end of the fitting *j*' has longitudinal grooves *l*² and the packing gland *l*³ is provided with radial slots *l*⁴ which communicate with an annular groove *l*⁵. A frangible disc *l*⁶ is seated upon an annular sealing washer or gasket *l*⁷ and the valve stem maintains the elements in a sealed condition. The usual frangible disc *l*⁸, seated upon the annular washer *l*⁹ is adapted to be ruptured by the cutter mechanism described hereinbefore. Although the disc *l*⁷ is seated against a shearing edge of smaller diameter than that of the disc *l*⁹, it is designed to rupture at a pressure lower than the bursting pressure of the latter disc. When, therefore, the pressure in the container becomes excessive the disc *l*⁶ will rupture against the shearing edge formed by the hole through the valve stem *l*. Upon this rupturing the contents of the container will pass through the hole *l*', slots *l*⁴, annular groove *l*⁵, and longitudinal grooves *l*², thus escaping to the atmosphere. A cap *l*¹⁰ may be screwed over the top of the fitting *j*' to protect the mechanism contained therein. In this form the functioning of the one disc is not dependent upon that of the other and the desired safety precaution is obtained without jeopardizing the successful operation of the rest of the system.

I claim as my invention:

1. A fire extinguishing system comprising a main fire extinguishing discharge line, means for maintaining a fire extinguishing medium under pressure, a piston guide, a piston movable therein, means to connect the piston to control the operation of a portion of the first means, means to supply a portion of said fire extinguishing medium under pressure to one side of said piston, and means to direct said portion of the fire extinguishing medium into the main fire extinguishing medium discharge line after the piston has reached the end of its useful stroke.

2. In an apparatus of the character described, comprising a piston, a piston guide, a piston rod connecting the piston with apparatus to be operated thereby, a source of supply of gas under pressure, an inlet from the source into the piston guide for admitting gas under pressure to one side of the piston, a relief for preventing the building up of back pressure on the opposite side of the piston from the inlet, a port through said piston for allowing the escape of any gas leaking into the piston guide, a normally open check associated with said port, and yielding means normally holding said check open, said means being overcome by the admission of the gas to one side of the piston to close the check to prevent the escape of gas, and a discharge outlet communicating with the piston guide on the opposite side of the piston from the inlet to permit the release of the actuating gas when the piston has reached the end of its useful stroke.

3. In an apparatus for creating a uni-directional actuating force for the operation of devices for releasing a fire extinguishing medium under pressure, the combination of a piston, a piston guide, a piston rod connecting the piston with the devices to be operated, a source of supply of fire extinguishing medium under pressure, an inlet into the piston guide for admitting a portion of the fire extinguishing medium under pressure to one side of the piston, a non-return relief valve for preventing the building up of back pressure on the opposite side of the piston from the inlet, a port through said piston for allowing the escape of any gas leaking into the piston guide, a normally open check associated with said port, yielding means to hold said check in a normally open position, said means being overcome by the admission of the medium under pressure to one side of the piston to close the check to prevent the escape of the actuating gas, a discharge outlet to permit the release of the fire extinguishing medium when the piston has reached the end of its useful stroke, and means connecting the discharge to the main fire extinguishing medium discharge line.

4. In an apparatus of the character described, a piston, a piston guide, a piston rod connecting the piston with apparatus to be operated thereby, a source of supply of gas under pressure, a supply line communicating with the source, an inlet from the supply line into the piston guide for admitting gas under pressure to one side of the piston, means for preventing the building up of back pressure on the opposite side of the piston from the inlet, and a bleed port freely communicating with the inlet and a region of relatively low pressure to prevent the forward movement of the piston by the pressure of gas leaking into the piston guide and gradually relieve the gas pressure exerted on the piston.

5. A fire extinguishing system comprising a fire extinguishing discharge line, means for maintaining a fire extinguishing medium under pressure, a piston guide, a piston movable therein, means to connect the piston to control the discharge of a portion of the fire extinguishing medium by controlling the operation of a portion of the first means, means to supply another portion of said fire extinguishing medium under pressure to one side of said piston, and means rendered operative by the piston to release said portion of the fire extinguishing medium after the piston has reached the end of its useful stroke.

6. In an apparatus of the character described, a piston, a piston guide, a piston rod connecting the piston with apparatus to be operated thereby, a source of supply of gas under pressure, a supply line communicating with the source, an inlet from the supply line into the piston guide for admitting gas under pressure to one side of the piston, and a bleed port freely communicating with the inlet and a region of relatively low pressure to prevent the forward movement of the piston by the pressure of gas leaking into the piston guide and gradually relieve the gas pressure exerted on the piston.

7. In an apparatus of the character described, comprising a piston, a piston guide, a piston rod connecting the piston with apparatus to be operated thereby, a source of supply of gas under pressure, an inlet from the source into the piston guide for admitting gas under pressure to one side of the piston, a relief for preventing the building up of back pressure on the opposite side of the piston from the inlet, a port communicating with

- the inlet and a region of relatively low pressure for allowing the escape of any gas leaking into the piston guide, a normally open check associated with said port, and yielding means normally holding said check open, said means being overcome by the admission of the gas to one side of the piston to close the check to prevent the escape of gas, and a discharge outlet communicating with the piston guide on the opposite side of the piston from the inlet when the piston is in its normal inoperative position, to permit the release of the actuating gas when the piston has reached the end of its useful stroke.
8. In an apparatus of the character described, the combination of a container for a medium under pressure, a releasing device associated therewith, means operable by the released medium and including an operating connection to the releasing device, and means normally closing off the operating connection for preventing operation of the last named means, means to render the preventing means ineffective, and means actuated by the last named means to actuate the releasing means.
9. In an apparatus of the character described, the combination of a container for a medium under pressure, a releasing device associated therewith, means operable by the released medium and including an operating connection to the releasing device, and means normally closing off the operating connection for preventing operation of the last named means, means to render the preventing means ineffective, and flexible means actuated by the last named means to actuate the releasing means.
10. In an apparatus of the character described, the combination of a plurality of containers for a fire extinguishing medium, medium releasing devices associated with the containers, a fluid pressure operated uni-directional actuating force producing device apart from the containers, an operating connection connecting the last named device with the medium releasing devices for effecting operation thereof, a control cylinder containing a medium under pressure, means for discharging said pressure medium in a direction for operating said actuating force producing device with the medium under pressure, and means independent of the actuating force producing device for preventing the operation of said actuating force producing device due to an accidental discharge of the actuating medium from the control cylinder in the direction for operating said actuating force producing device.
11. In an apparatus of the character described, the combination of a container for a medium under pressure, a releasing device associated therewith, means operable by the released medium and including an operating connection to the releasing device, means normally closing off the operating connection for preventing operation of the last named means, means to render the preventing means ineffective, and means actuated by the last named means to actuate the releasing means.
12. In an apparatus of the character described, the combination of a plurality of containers for a fire extinguishing medium, medium releasing devices associated with the containers, a fluid pressure operated uni-directional actuating force producing device apart from the containers, an operating connection connecting the last named device with the medium releasing devices for effecting operation thereof, a control cylinder containing a medium under pressure, means for discharging said pressure medium in a direction for operating said actuating force producing device with the medium under pressure, and means independent of the actuating force producing device for preventing accidental discharge of the actuating medium from the control cylinder in the direction for operating said actuating force producing device.
13. A fire extinguishing system comprising a main fire extinguishing line, means for maintaining a fire extinguishing medium under pressure, a piston guide, a piston movable therein, means to connect the piston to control the operation of the first means, means to supply a fire extinguishing medium under pressure to one side of said piston, and means to direct said last named fire extinguishing medium into the main fire extinguishing medium discharge line after the piston has reached the end of its useful stroke.
14. In an apparatus for creating a uni-directional actuating force for the operation of devices for releasing a fire extinguishing medium under pressure, the combination of a piston, a piston guide, a piston rod connecting the piston with the devices to be operated, a source of supply of fire extinguishing medium under pressure, an inlet into the piston guide for admitting a fire extinguishing medium under pressure to one side of the piston, a non-return relief valve for preventing the building up of back pressure on the opposite side of the piston from the inlet, a port through said piston for allowing the escape of any gas leaking into the piston guide, a normally open check associated with said port, yielding means to hold said check in a normally open position, said means being overcome by the admission of the medium under pressure to one side of the piston to close the check to prevent the escape of the actuating gas, a discharge outlet to permit the release of the fire extinguishing medium when the piston has reached the end of its useful stroke, and means connecting the discharge to the main fire extinguishing medium discharge line.

DANIEL MAPES.
